UNITED STATES PATENT OFFICE.

LEAH G. MILKES, OF MINNEAPOLIS, MINNESOTA, ASSIGNOR TO VENUS MANUFACTURING COMPANY, OF MINNEAPOLIS, MINNESOTA, A CORPORATION OF MINNESOTA.

REVERSIBLE CUFF.

1,309,043.

Specification of Letters Patent.

Patented July 8, 1919.

Application filed July 27, 1918. Serial No. 247,059.

To all whom it may concern:

Be it known that I, LEAH G. MILKES, a citizen of the United States, residing at Minneapolis, in the county of Hennepin and State of Minnesota, have invented certain new and useful Improvements in Reversible Cuffs; and I do hereby declare the following to be a full, clear, and exact description of the invention, such as will enable others skilled in the art to which it appertains to make and use the same.

My present invention relates to reversible shirt cuffs and is in the nature of a modification of the cuff disclosed and broadly claimed in my pending application S. N. 231,199, filed April 27, 1918.

Particularly, the present invention has for its object to provide a reversible cuff which is adapted to be overlapped and buttoned together by a single or common button, regardless of which side out the reversible cuff is turned.

The present reversible cuff, like that of my prior application, is a pocket-like structure, that is, the cuff is made with two so-called flaps that are stitched together at their outer edges and ends, and one of which flaps is attached to a shirt sleeve, while the other flap is left loose at its inner edge, thus providing a cuff that is adapted to be turned inside out.

The invention is illustrated in the accompanying drawings, wherein like characters indicate like parts throughout the several views.

Referring to the drawings,

Figure 1 is a perspective view showing a sleeve with the improved cuff attached, the said cuff being turned with its loose flap on the inner side of the cuff, the said inner side of the cuff being exposed chiefly in view;

Fig. 2 shows the same adjustment of the cuff as illustrated in Fig. 1, but views the same from the back or side of the cuff;

Fig. 3 is a view corresponding to Fig. 1, but showing the cuff turned with its loose flap on the outer side of the cuff; and

Figs. 1^a and 3^a are diagrammatic cross sections of the cuff, but Fig. 1^a corresponds in its adjustment to Figs. 1 and 2, while Fig. 3^a corresponds in its adjustment to Fig. 3.

The numeral 4 indicates a sleeve which may be assumed to be the sleeve of a man's

shirt. The cuff, as already indicated, is made up of two flaps 5 and 6. The so-called flap 5, as shown, is made two-ply, while the flap 6, as shown, is single-ply but might also be made double-ply. The two flaps, at their outer edges and ends, are preferably connected by French seams which give the cuff a finished appearance, regardless of which side out it is turned.

Near one end of the cuff, the flaps 5 and 6 are provided, respectively, with button holes 5^a and 6^a, that align in both adjustments of the cuff. Near the other end of the cuff, the flap 5 is provided with a button 5^b, and aligned therewith, the flap 6 is provided with a button hole 6^b. This relative arrangement of button and buttonholes and flaps is important and makes possible the following use of the button in connection with the buttonholes.

In the adjustment of the cuff shown in Figs. 1, 2 and 1^a, the loose flap 6 is inside of the cuff, and in this adjustment, the button 5^b projects on that side of the flaps 5 that is away from the buttonholes 6^b, and then stands in position to be inserted through the aligned button holes 5^a and 6^a.

In the adjustment of the cuff shown in Figs. 3 and 3^a, the loose flap 6 is on the outside of the cuff, and in this adjustment, the button 5^b is turned toward and must be passed through the aligned buttonhole 6^b, so that it may then be inserted through the aligned buttonholes 5^a and 6^a. Thus it will be seen that a single button in both adjustments of the cuff serves to fasten the sleeve. This is an extremely simple and efficient arrangement.

The purpose of turning the cuff inside out is, of course, to afford a clean outer cuff surface after one surface of the cuff has been soiled.

This particular design of the cuff is especially adapted for use on low-priced shirts where it is not desirable to use cuff buttons, but rather to use an attached button where it is further desirable to have a reversible cuff.

What I claim is:

A sleeve having a reversible cuff made up of two flaps, the said flaps being connected at their outer edges and ends and one of the flaps being connected to the sleeve at its inner edge, the inner edge of the other flap being loose to permit reversing of the cuff,

the said two flaps, near one end of the cuff, having registering buttonholes, one of said flaps, near the other end of the cuff having an attached button, and the other flap having a buttonhole registering with said button.

In testimony whereof I affix my signature in presence of two witnesses.

LEAH G. MILKES.
